(57) **CLAIM**

The ornamental design for a medical instrument for coagulation of tissue, as shown and described.

DESCRIPTION

FIG. 1 is a side left perspective view of a medical instrument for coagulation of tissue in accordance with the new design;

FIG. 2 is a left side view thereof;

FIG. 3 is a right side view thereof;

FIG. 4 is a top left view thereof;

FIG. 5 is a top right view thereof;

FIG. 6 is an enlarged front view thereof; and,

FIG. 7 is an enlarged rear view thereof.

FIGS. 1-6 show a break indicating no particular length. The broken line showing in FIGS. 1-7 is included for the purpose of illustrating portions of the medical instrument for coagulation of tissue that form no part of the claimed design.

1 Claim, 7 Drawing Sheets

FIG. 2

FIG. 5

FIG. 7
